August Mr. Tressow

UNITED STATES PATENT OFFICE.

CHARLES H. SKINNER, OF NEWARK, NEW JERSEY.

MACHINE FOR CURLING HAT-BRIMS.

SPECIFICATION forming part of Letters Patent No. 642,726, dated February 6, 1900.

Application filed April 1, 1898. Serial No. 676,097. (No model.)

To all whom it may concern:

Be it known that I, CHARLES H. SKINNER, a citizen of the United States, residing at Newark, in the county of Essex and State of New

5 Jersey, have invented certain new and useful Improvements in Machines for Curling Hat-Brims; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 My invention relates to the machinery employed for curling the brim on a hat, and in addition to possessing one signal advantage in the method of curling said brim as against any of the present machines in use for such 20 purposes the whole construction of my machine is improved by the introduction of new elements and combinations of elements, resulting in greater simplicity of coöperation between the different parts.

25 In describing my invention I shall call attention to the accompanying drawings, where like letters of reference indicate corresponding parts in the different views.

Figure 1 shows a side view of my improved 30 brim-curling machine; Fig. 2, a rear end view of Fig. 1 with parts omitted for the sake of clearness in illustration; Fig. 3, a side view of the bracket supporting the chain-gearing, with one of the chain-drums shown in section; 35 Fig. 4, a top view of the part of the chain which forms the brim-curling arc, the chain-drums with the upper parts broken off, and a section of the gear-wheel that meshes with the chain-teeth; Fig. 5, a top view of a fe- 40 male link of the curling-chain; Fig. 6, a side view of the same; Fig. 7, a front view of said female link; Fig. 8, a side view of a male link; Fig. 9, a front view of the male link, and Fig. 10 is a detail view of the bracket G.

45 In Fig. 1, A' indicates a disk having teeth cut in the rim thereof and having an upper part A², which acts as a guide for the formation of the curling-arc caused by the flanges L² of the links coming in contact with the rim 50 of said part A² successively, as will be more fully explained as the description proceeds. Secured in a suitable manner to this disk A'

is a perpendicular shaft B, having at its nether end a pinion C attached, which pinion C gears into a worm D, mounted on a shaft E, the 55 said shaft being supported in the bracket E', which is bolted to the frame A.

Frame A is a U-formed shell, as illustrated in cross-section in Fig. 2, having, as above indicated, the perpendicular shaft B running 60 down through the middle thereof and supporting the disk A' at the top. Extending from the top is a bracket-arm F, to which is bolted or otherwise attached a bracket G. On this bracket there are placed pivotally two chain- 65 drums H' and H², of which H' is shown in section in Fig. 3 mounted on the bracket and secured there by a stud H³, shown in full. Said stud has a flange H⁴, which bears on the top of the drum, and as the nethermost part 70 of the stud H⁵ is screw-cut when a nut is screwed on said part it will be seen to afford the necessary binding means for the drums on the bracket. Around these drums H' and 75 H², following the dotted line H, which dotted line indicates the travel of the chain-links, is the brim-curling chain K, composed of alternating male and female links K' K² K³ K⁴, &c.—in fact as many as will be found necessary to form on part of its circumference 80 the length of an arc requisite to form a good curl on the hat-brim. The construction of these links will best be observed in Figs. 5 to 9. K' represents a female link and is constructed as follows: Cut out between the 85 overlapping top and bottom parts L' and L² is a semicircular cavity L³, which cavity is notched so that the raised edge of each notch will carry the hat-brim along with it during the operation of the curling-iron M on the 90 brim. The rear part of the link has an upper flange L⁴ and a lower flange L⁵. Between these flanges the flange N' of male links N will be pivoted on each side by their respective pins O. Said pins consequently act as 95 the link-pins that join the links of the brim-curling chain together; but they have one more function and that is the function of a gear-tooth. To that effect the lower part O' of each pin O is thicker in diameter and 100 so gaged that it meshes with the indents O², cut in the rim of the disk A'. The bracket G supports these teeth in a horizontal position on their travel around the drums H' and

H^2 , and in addition thereto a support I can be attached by screws to the under side of the bracket G in order to prevent any sagging of the chain in the rear. The other 5 part necessary to perform the curling operation and complete the mechanism is the curling-iron M. As best seen in Fig. 1, said iron is attached to a hollow part M', to which any adequate heating means can be attached. 10 M' is secured to an arm P, pivoted in the recess R^3 of the upper lever-arm R' of a treadle-lever R, said treadle-lever itself pivoted in the bracket Q by a pin Q'. The arm P is further supported and regulated by two pins 15 P' and P², both integral therewith, said pins passing through holes in the lever-arm R', each having a spring, respectively, P³, coiled around P', and P⁴, coiled around P². The springs are held in compression between the 20 lever-arm R' and the nuts P⁵ and P⁶ on their respective screw-cut ends of the pins P' and P². The springy elastic position thus afforded the arm R is controlled by a set-screw P⁷, counteracting the upward action of the spring 25 coiled around P', and by set-screw P⁸, counteracting the rearward action of the spring around P². The lower lever-arm R² of the lever R has a treadle S and an arm S', to the end of which arm one end of a coiled spring T is attached, the other end of the spring being secured to a pin T', fixed in the frame A, the consequence of this being that the contracting power of the spring T will always hold the lower arm R² up against the pin T', which 30 as the entire lever R moves as one unitary element will hold the curling-iron M in the proper position, as shown in Fig. 1, so that when the foot is placed on the treadle S the iron M is removed out of the groove in the 35 40 curling-chain.

The coöperative action of the different parts of the machine described will thus be seen to be the following: When a motive power is applied to the driving-pulley V, the shaft E, 45 carrying the worm D, will be rotated, and the pinion C, attached to the lower end of the perpendicular shaft B, meshing with said worm, will consequently give motion to said shaft and to the disk A', resting on the top 50 of frame A. As this disk A' is furnished with the indents O² and consequent projections that might properly be termed "gear-teeth" and said teeth intermesh with the link-pins O', a rotary motion around the chain-drums H' and H² will be given to the brim-curling chain K. Calling attention to the lower part L² of, for instance, the link K', the surface W of said link will contact with the rim of the upper part A² on the disk A', 55 and speaking of all the links as they circulate and successively contact with a part of the circumference of A² it will be seen that they will form an inverted arc, and as their individual grooves L³ are brought in alinement they will form a closed groove by reason 60 of their being guided against part of the circumference of the upper part A² of the disk A'.

This forms the nucleus of my invention. The inverted arc thus formed on the periphery of the disk A² will of course depend on the radius of the said disk, which again will influence the number of links that will be needed to aline each other, so as to form the continuous brim-curling groove. As soon as the links leave the disk A² and are drawn around the drums they separate and the arc is then broken. The curling-iron M necessary for the formation of the curve in the hat-brim is, as described heretofore, adjustably secured by means of the pins P' and P². The holes in the upper lever-arm R² are, furthermore, elongated—as, for example, the left-hand hole R⁴ seen in Fig. 1—so that the pin in the arm P resting therein has a certain play horizontally back and forth. Another elongated or slotted hole H³ will be found in the bracket G in order to permit the tightening of the link-chain, so as to take up the slack therein. Having thus described my improved machine, I can now refer to the advantage possessed by it in the method of curling hat-brims mentioned in my preamble by means of my improved link curling-chain. It is a well-known fact that in all the brim-curling machines now in use the brim is recipient of a glazed shiny surface received during the process of curling, which is detrimental to the hat, inasmuch as it necessitates the rubbing off of said glazed surface, so as to present the same frowzy or glossy appearance as the rest 95 of the hat. This of course reduces the thickness of the brim and weakens it considerably and does not render the quality of the hat what it might otherwise be. It is this fault in the curling means I have overcome by 100 means of the indented continuously-moving groove formed by the links in the curling-chain as they in succession form the inverted arc heretofore described by being guided on and by the revolving disk A'. 105 110

It will of course readily be understood, that the mere mechanical accessories employed in revolving and supporting the curling-chain, as well as minor details in the general construction of my machine, can be varied without departing from my invention. I, further, do not desire to limit myself to the use of this chain in hat machinery alone, inasmuch as the closed groove in the arc formed from an external center can be put to many useful 115 purposes besides the above-described use in curling hat-brims.

What I therefore claim, and desire to secure protection for by Letters Patent, is—

1. A chain consisting of grooved links, suitable drums having said chain revolving around them, means external to the chain closing the links together so as to form a continuous groove on a given part of the periphery. 125

2. A chain consisting of grooved links, the groove on each link furnished with catching means, suitable drums having the chain revolving around them, an inverted arc, formed 130

on the periphery of the chain having its center outside of the said periphery, closing the links so as to form a continuous groove.

3. The combination of a chain, consisting 5 of grooved links moving around suitable drums, with means external to the periphery of said chain forming an inverted arc on the periphery causing the links to close and form a continuous groove.

10 4. As a new mechanical device, a revolving grooved chain having an inverted arc formed on its periphery, means forming said arc having their center lying outside of the periphery of said chain, with coöperative gearing means 15 connecting the said elements.

5. As a new mechanical device, a chain composed of male and female links alternating with each other, constructed, connected and revolved as described, each link having a groove 20 furnished with catching means, an inverted arc formed in the periphery of said chain, a continuous groove formed in said arc by the links having full lateral contact with each other for the purposes set forth.

25 6. The combination of a chain having grooved links, suitable drums having the chain revolving around them forming an inverted arc on a part of the periphery having a continuous groove; with a revolving toothed 30 wheel external to said periphery engaging said links so as to move the chain around the drums.

7. In a machine the combination of a chain having grooved links, drums having the chain 35 revolving around them so as to form an inverted arc with a continuous groove formed in such arc, pins joining said links and acting as teeth, a horizontal disk having a guide-recess formed thereon, indents cut out in the 40 rim of the said disk fitting the link-pins and gearing means giving motion to said disk and chain.

8. The combination in a machine of a chain having grooved links, pins joining said links 45 together acting as teeth, a horizontal disk having a guide-recess formed thereon for guiding the grooved links, indents cut out in the rim of the disk fitting the link-pins, gearing means giving motion to said disk and chain substantially as described.

50 9. The combination in a brim-curling machine of the curling-iron with a grooved chain suitably supported, the said chain on a certain part of its periphery forming an inverted ed arc having a closed groove, a horizontal

disk mounted on the top of the frame of the machine, having a guideway coöperating with the chain, indents cut in the rim of said disk meshing with means formed on the chain-links, gearing revolving the disk and chain 60 substantially as described.

10. In a brim-curling machine the combination of the curling-iron adjustably secured in the upper arm of a pivoted treadle-lever, a horizontally-revolving disk supported on 65 the top of the machine-frame furnished with teeth and having a guideway, a chain moved by and simultaneous with the said horizontal disk, each link of the said chain having a groove and a guide-flange, the said flanges 70 by contact with the guideway on the horizontal disk forming an inverted arc in the said chain, the individual grooves of each link forming a curved closed groove for the purposes set forth, substantially as described. 75

11. In a brim-curling machine the combination of the curling-iron secured to a treadle-lever, a pivoted spring-controlled arm supporting said curling-iron, a horizontal disk furnished with teeth and having a guideway, 80 a chain having grooved links forming an inverted arc by contact with the said disk, the link-pins of said chain gearing with the disk-teeth, two horizontally-adjustable drums pivotally attached to a bracket suitably secured 85 to the frame guiding the said chain for the purposes set forth, substantially as illustrated and described.

12. In a brim-curling machine the combination of the curling-iron adjustably secured 90 to a treadle-lever, a horizontal disk furnished with teeth and having a guideway formed thereon, a perpendicular shaft attached to said disk, a pinion secured to the lower end of said shaft, a worm, having motive power 95 suitably transmitted to it, revolving said pinion, a chain composed of grooved links whose link-pins intermesh with the disk-teeth, revolved around two adjustably-pivoted drums, an arc formed in said chain by contact with 100 the guideway on the horizontal disk for the purposes specified substantially as illustrated and described.

In testimony that I claim the foregoing I have hereunto set my hand this 26th day of 105 March, A. D. 1898.

CHARLES H. SKINNER.
